UNITED STATES PATENT OFFICE.

REINHARDT DAAE, OF YOUNGSTOWN, OHIO.

FUEL FEED FOR GAS PRODUCERS.

Application filed June 7, 1923. Serial No. 643,908.

To all whom it may concern:

Be it known that I, REINHARDT DAAE, a citizen of the United States, residing at Youngstown, in the county of Mahoning and State of Ohio, have invented a new and useful Improvement in Fuel Feeds for Gas Producers, of which the following is a full, clear, and exact description.

The present invention relates broadly to fuel feeding mechanism, and more particularly to mechanism of this character especially adapted for feeding fuel to gas producers.

It has heretofore been proposed to provide rotary fuel feeding members for gas producers, which members receive their supply of fuel from reciprocating or frictional fuel feeding means. Such combinations have proven highly desirable for the reason that the rotary feeding members form partial seals for the producers, and the frictional fuel feeding means deliver fuel thereto under such conditions that the possibility of breakage is minimized. It has been found, however, that considerable difficulty is encountered in the operation of such frictional fuel feeds due to the deposit thereon of tarry material which passes the rotary feed.

Further objections have arisen due to the passage of foreign material into the feeding pockets of the rotary feed and the projection of such material beyond the discharge end of the pockets whereby damage to the enclosing casing has frequently resulted.

By the present invention there is provided a fuel feeding mechanism of this character, adapted to insure a more uniform feed of fuel without danger of any breakage and without liability of clogging up by reason of the formation of tarry matter within the producer.

In the accompanying drawings there is shown, for purposes of illustration only, a preferred embodiment of the present invention, it being understood that the drawings do not define the limits of this invention, as changes may be made in the construction and operation herein disclosed without departing from the spirit or scope of my broader claims.

In the drawings,—

Figure 1 is a vertical sectional view through a fuel feed embodying the present invention, the section being taken on the line I—I of Figure 2;

Figure 2 is a side elevation of the construction illustrated in Figure 1;

Figure 3 is a vertical sectional view through the fuel feed on the line III—III of Figure 1;

Figure 4 is a detail view illustrating a portion of the actuating mechanism for the frictional fuel feed; and

Figure 5 is a detail view illustrating a slightly modified form of frictional fuel feeding mechanism.

In accordance with the present invention, there is provided a producer body 2 of any standard construction, adapted to be closed by a cover 3 having means for insuring a water seal 4 between the body of the producer and the cover.

Preferably the producer is of the type in which there is a relative rotational movement between the body and the cover, such movement being obtained either by rotating the producer body or maintaining this body stationary and rotating the cover. In the illustrated embodiment of the invention the cover is adapted to be rotated at any desired speed by means of a gear 5 driven from a suitable source of power, not shown. During this relative rotational movement, the producer is adapted to have fuel fed thereto in measured quantities through a fuel feeding opening 6 provided in the cover.

The mechanism for feeding the fuel may conveniently comprise a fuel chute 7 having its vertical axis substantially coincident with the axis of rotation of the cover, whereby coal may be continuously supplied thereto during the operation of the producer. Forming the bottom of the chute 7 is a slide plate 8 on which is adapted to reciprocate a frictional fuel feeding member 9. This frictional fuel feeding member is adapted to be reciprocated by means of links 10 pivotally connected at one end to the member and at their opposite ends to the crank arm 11. This crank arm is carried by a transversely extending shaft 12 from which projects a second crank 13 adapted to be operated as hereinafter more fully described. During the movement of the fuel feeding member 9 to the right as viewed in Figure 1, the effective area of its upper surface for the reception of fuel will be increased, whereby upon movement thereof in the opposite direction a certain definite quantity of the fuel carried thereby will be frictionally fed forwardly by the inclined back wall

14 of the feed chute. This inclination is highly desirable as it insures a passage of fuel to the frictional feeding member and more effectively assists in the pushing of the fuel from such member on its back stroke.

5 It will be apparent that the surfaces which support the frictional feeding member are in sliding engagement therewith, whereby reciprocation of the member 9 tends to prevent 10 the accumulation of any foreign material on the surfaces. To further assist in this respect, there are provided water connections 15 tending to continuously supply a predetermined amount of water to these 15 surfaces whereby the adherence of tar is prevented. In this manner uniform operation of the frictional feeding member is insured at all times.

The front end of the frictional feeding 20 member preferably projects into a casing 16 into which the member discharges through the lateral opening 17 in the chute. The amount of projection is determined generally by the dimensions of the opening 17 and the 25 character of the material being handled, to insure that the material may always assume an angle of repose. The extent of the opening 17 may be varied at will by an adjustable gate 18. For receiving the fuel as discharged by 30 the frictional fuel feed, there is provided a rotary feeding member 19 having a series of pockets 20 therein. These pockets are so shaped that the area at the discharge portions thereof is as great as the greatest area 35 at any point within the pocket, whereby the free discharge of all of the fuel therefrom is insured. This feature is of considerable importance, as it has been found that overhanging ledges and the like not only tend 40 to collect tar but to prevent the free discharge of the fuel.

I have found that in order to secure efficient results, it is not practicable to drop the fuel downwardly onto the rotary fuel 45 feeding member, as lumps of the coal frequently assume such positions as to interfere with the rotation of the rotary member in the casing 16. For this reason the frictional fuel feeding means is located entirely 50 to one side of the rotary member and is preferably below such member, whereby the fuel is fed laterally into the successive pockets as they are brought into position. During rotation of the member 19 in the 55 direction of the arrow *a*, the filled pockets are brought successively into cooperative position beneath a crushing, distributing and wiping roller 21, which roller tends to remove any fuel or foreign material projecting 60 beyond the openings of the pockets, and to compact the material therein whereby the filled pockets may easily pass into such position as required within the casing.

65 To prevent the accidental passage of any fuel means, said plunger having a central pas-

sage therethrough and lateral openings from 70 tion of the rotary member, there is provided a transversely extending angle plate 22. Continued rotation brings the pockets successively into position, whereby they may 75 discharge into the outlet 23 communicating with the opening 6 in the cover. In order to effectively distribute the discharged fuel and feed it uniformly over the fuel bed in the body of the producer, there is provided 80 a half-bell 24. This half-bell is preferably so carried that it may be adjusted radially to vary the fuel feed to an extent determined by the length of the slotted opening 25.

The operation of the parts in timed relation to the relative rotational movement between the producer and cover may be obtained by mounting on the cover a shaft 26 85 extending radially or diametrically thereof and carrying at its outer end a bevel gear 27 adapted to project through the cover and engage the gear teeth 28 carried by the upper end of the producer body. At an intermediate point, the shaft 26 carries a spur gear 29 meshing with a similar gear 30 on the shaft 31. This gear in turn drives a spur gear 32 meshing with an idler gear 33 for driving the gear 34 carried by the shaft 35 upon which is mounted the roller 90 21. At its opposite end the roller shaft is provided with a gear 36 meshing with a pinion 37 on a transversely extending shaft 38. At its opposite end this shaft carries a 95 disk 39 formed with a diametrically extending slot 40. Adjustably secured within this slot is one end of a pitman 41, the opposite end of which is adjustably connected to the crank arm 13, as clearly shown in Figure 1. By reason of this construction it will be 100 apparent that the roller 21 is continuously rotated during the movement of the cover 3, at a speed higher than the speed of rotation of the rotary feeding member 19 and in the same direction, whereby the engaging 105 surfaces move in opposite directions, thereby tending to effectively remove any projecting material. The shaft 38 is also operated at a higher speed than the speed 110 of rotation of the rotary feeding member, whereby the frictional feeding mechanism has imparted thereto a plurality of reciprocatory movements during such time as each of the pockets 20 is in fuel receiving 115 position. This operation has been found highly desirable, as with a short stroke of the member 9 much more uniform fuel feeding is possible than with a longer stroke. This result is probably due to the vibratory 120 movement imparted to the coal whereby a constant feed through the chute 7 is insured, thereby maintaining a more compact body of fuel in position to be discharged by the frictional fuel feed.

125 It will be apparent that by adjusting the 130

position of the pitman 41 with respect to the slot 40 in the actuating disk 39, the length of stroke of the pitman may be varied at will. Also, by means of the adjusting mechanism 42 carried by the crank arm 13, the operation of the frictional feeding member 9 may be further varied.

In Figure 5 there is illustrated a slightly modified form of the invention in which 10 parts corresponding to the parts already described have been designated by the same reference characters as those heretofore used but having a prime affixed thereto. In this form of the invention the member 9' 15 is slightly inclined downwardly toward its discharge end. This construction has been found desirable in certain gas producers, due to the character of the fuel being handled.

Considerable difficulty is experienced in 20 the operation of gas producers having rotary fuel feeding means, due to the tendency of the same to expand under the influence of the heat and bind. In order 25 to overcome this objection, the rotary member 19 is preferably provided with a series of chambers 43 which may be filled with asbestos or other material tending to impart the desired characteristics. The ends 30 or heads 44 of the rotary member are preferably mounted to rotate on flat bearings in the sides of the casing 16, whereby in the event of any tar deposits on these surfaces it may work outwardly therethrough 35 without interfering with the rotation of the parts. At the outside of the casing the tar is permitted to drop downwardly into the bearing brackets 45.

The advantages of the present invention 40 arise from the provision of a frictional fuel feeding mechanism delivering to a rotary feeder and so located as to be laterally disposed with respect to the rotary feeder. Further advantages arise from the 45 construction of the frictional feeding mechanism whereby the operation is not impaired by the action of the tar produced by the producer.

Still further advantages arise from the 50 construction of the rotary feeding member and the roller cooperating therewith, together with the half-bell for effectively distributing the fuel.

I claim:

1. In a fuel feed for gas producers, a chute, a casing, fuel feeding means at the lower end of the chute for delivering fuel to one side of the casing, mechanism for operating said fuel feeding means to periodically deliver predetermined quantities of fuel thereby, a rotary feeder in the casing having a pocket which is brought to filling position relative to the feeding means, the feeder being so positioned that fuel which projects beyond the pocket will

fall back toward the feeding means, substantially as described.

2. In a fuel feed for gas producers, a chute, a casing adapted to receive fuel from the chute, means for feeding fuel from the chute to the casing, mechanism for operating said fuel feeding means to periodically deliver predetermined quantities of fuel thereby, a rotary feeding member in the casing having a feed pocket, a rotary wiper 70 co-acting with the feeding member, and means for causing the fuel feeding member and wiper to rotate in the same direction so that surplus fuel will be wiped from the pocket, substantially as described. 75

3. In a fuel feed for gas producers, a casing, a rotary feeding member in said casing provided with a fuel pocket, a chute, frictional fuel feeding means located in said chute laterally of said rotary feeding member 80 and below the top thereof for feeding fuel thereto, and operating mechanism for said fuel feeding means, substantially as described. 85

4. In a fuel feed for gas producers, a casing, a rotary feeding member in said casing provided with a pocket, a chute terminating at one side of the casing below the top of the rotary feeding member, a frictional fuel feeding means for transferring fuel from 90 said chute to said member and operating mechanism for said fuel feeding means, substantially as described. 95

5. In a fuel feed for gas producers, a casing, a rotary feeding member in said casing 100 provided with a plurality of fuel receiving pockets, vibrating frictional fuel feeding means for delivering fuel to said pockets, and means for causing the frictional fuel feeding means to make a number of short 105 and rapid vibrations while each of said pockets is in fuel receiving position, substantially as described.

6. In a fuel feed for gas producers, a casing, a rotary feeding member in said casing 110 provided with a plurality of fuel pockets, a reciprocating fuel feeding member for delivering fuel to said pockets, and means for imparting a plurality of short and rapid 115 reciprocations to said reciprocating means while each pocket is in fuel receiving position, substantially as described.

7. In a fuel feed for gas producers, a casing, a rotary feeding member in said casing provided with a plurality of fuel receiving 120 pockets, vibrating frictional fuel feeding means for delivering fuel to said pockets through an opening in the casing, means for causing the frictional fuel feeding means to make a number of short and rapid vibrations while each of said pockets is in fuel receiving position, and an adjustable gate 125 for said opening for varying the amount of fuel fed by the said fuel feeding means, substantially as described. 130

- 4
8. In a fuel feed for gas producers, a casing, a rotary feeding member in said casing, provided with a plurality of fuel pockets, a reciprocating fuel feeding member for delivering fuel to said pockets through an opening in the casing, means for imparting a plurality of short and rapid reciprocations to said reciprocating means while each pocket is in fuel receiving position, and an adjustable gate for said opening for varying the amount of fuel fed by said reciprocating member, substantially as described.
9. In a fuel feed for gas producers, a fuel feed chute, a reciprocatory member forming the bottom of said chute, and means for supplying a stream of water to the fuel feed-
- ing surface of said member during its reciprocation, substantially as described.
10. In a fuel feed for gas producers, a casing, a feeding member in the casing having a fuel pocket therein, means for slowly moving the feeding member to shift the pocket from receiving to delivering position, there being an opening in the casing through which the fuel is fed to the feeding member, a vibrating feeder in the opening, and means vibrating the feeder at a high speed when compared to the speed of the feeding member, substantially as described. 20 25
- In testimony whereof I have hereunto set my hand. 30

REINHARDT DAAE.

- 4
8. In a fuel feed for gas producers, a casing, a rotary feeding member in said casing provided with a plurality of fuel pockets, a reciprocating fuel feeding member for delivering fuel to said pockets through an opening in the casing, means for imparting a plurality of short and rapid reciprocations to said reciprocating means while each pocket is in fuel receiving position, and an adjustable gate for said opening for varying the amount of fuel fed by said reciprocating member, substantially as described.
9. In a fuel feed for gas producers, a fuel feed chute, a reciprocatory member forming the bottom of said chute, and means for supplying a stream of water to the fuel feed-
- ing surface of said member during its reciprocation, substantially as described.
10. In a fuel feed for gas producers, a casing, a feeding member in the casing having a fuel pocket therein, means for slowly moving the feeding member to shift the pocket from receiving to delivering position, there being an opening in the casing through which the fuel is fed to the feeding member, a vibrating feeder in the opening, and means vibrating the feeder at a high speed when compared to the speed of the feeding member, substantially as described. 20
- 25
15. In testimony whereof I have hereunto set my hand.

REINHARDT DAAE.

Certificate of Correction.

It is hereby certified that in Letters Patent No. 1,573,811, granted February 23, 1926, upon the application of Reinhardt Daae, of Youngstown, Ohio, for an improvement in "Fuel Feeds for Gas Producers," an error appears in the printed specification requiring correction as follows: Page 2, line 65, beginning with the word "means" strike out all to and including the word "from" in line 66, and insert instead *above and behind the roller 21 into a position where it would interfere with the rota-*; and that the said Letters Patent should be read with this correction therein that the same may conform to the record of the case in the Patent Office.

Signed and sealed this 6th day of April, A. D. 1926.
